UNITED STATES PATENT OFFICE

2,442,343

RAIL ANTICREEPER

Hugh C. Christie, Cocoli, C. Z.

Application March 20, 1947, Serial No. 736,019

2 Claims. (Cl. 238—325)

1

This invention relates to new and useful improvements in rail anti-creepers and the primary feature of the present invention is to provide a device for preventing longitudinal movement of the rails on their ties.

Another important feature of the present invention is to provide a device of the character referred to which can be readily and quickly applied to the rails by a usual rail pick.

A further feature of the present invention is to provide a rail anti-creep designed to be applied from either side of the rail by merely stretching the device so that the hooks provided at each end thereof grip the base flanges of the rail and said device is so designed to have a positive locking action on the rail and is held in place thereon through spring action.

A still further feature of the present invention is to provide a rail anti-creep of the class described that is simple and practical in construction, easily applied to and removed from a rail, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of a rail with the anti-creep device applied thereto.

Figure 2 is a sectional view of a rail shown in section, the anti-creep device applied to the rail.

Figure 3 is a side elevational view thereof.

Figure 4 is a perspective view of the anti-creep device.

Referring now to the drawings in detail wherein, for the purpose of illustration, I have disclosed a preferred embodiment of the present invention, the numeral 5 represents a portion of a standard rail having the usual form of bottom flange or base 6.

The anti-creep device designated generally by the numeral 7 comprises a one-piece resilient bar, preferably circular in cross-section.

Pairs of horizontally spaced substantially U-shaped hook members 8 and 9 are connected at their upper ends by integral horizontal pick-engaging loops 10 and 11.

The lower end of one of the hook members 8 and the lower end of one of the hook members 9 are connected by an integrally formed, horizon-

2 tally undulating body portion 12 formed of longitudinal loops 13.

The lower end of the other hook member 8 and the lower end of the other hook member 9 are bent around the body portion as at 14 for connecting thereto.

In use of the anti-creep device, the loop members 8 engage one side of the bottom flange 6 and the body portion 12 extends transversely beneath the rail 5. The loop 10 formed at the upper ends of members 9 is then engaged by a usual rail pick or the like (not shown), and in this manner the body is stretched or pulled outwardly under tension by the loops 13 of the body portion so that the hook members 9 engage the bottom flange 6 on the other side from the members 8 as shown in Figure 2. The loops 13 are adapted to bear against metal tie plate 15 of a tie 16, thereby preventing longitudinal movement of the rail.

20 In view of the foregoing description taken in conjunction with the accompanying drawings, it is believed that a clear understanding of the device will be quite apparent to those skilled in this art. A more detailed description is accordingly 25 deemed unnecessary.

It is to be understood, however, that even though there is herein shown and described a preferred embodiment of the invention, the same is susceptible to certain changes fully comprehended by the spirit of the invention as herein described and within the scope of the appended claims.

What I claim as new is:

1. A rail anti-creep of one piece construction 35 comprising pairs of opposed hook members adapted to grip the bottom flange of a rail on opposite sides of the rail, outwardly extended pick-engaging loops formed at the upper ends of each pair of hook members between the hooks 40 of each pair, and a resilient body portion extending transversely under the rail and connecting said opposed pairs of loops, said body portion adapted for transverse stretching under tension to permit engagement of the hook members with 45 the rail, and said body portion bearing transversely against the rail tie.

2. A rail anti-creep for attachment to the base of the rail comprising an elongated skeleton member of rod-like resilient material including a 50 body of zigzag form adapted to underlie said base crosswise thereof and to be stretched to elongate the same, end pairs of hooks on said body connected thereto in laterally spaced relation in each pair and adapted to straddle the edges of said base at widely separated points along each edge

and yieldingly engage said edge under reaction of said body, and pick engaging loops connecting the hooks together in pairs and extending longitudinally of the base outwardly beyond the pairs of hooks for the insertion of a pick therein between said loops and said edges of said base.

HUGH C. CHRISTIE.
